REPAIRING AND SPLICING KIT CONTAINER

John V. Nowicki, St. Paul, and Harold K. Gavere,
Marine-on-St. Croix, Minn., assignors to Minnesota
Mining & Manufacturing Co., St. Paul, Minn.

Filed Apr. 8, 1974, Ser. No. 458,641

Term of patent 14 years

Int. Cl. D9—01

U.S. Cl. D9—174

FIG. 1

FIG. 2

FIG. 4

FIG. 3

FIG. 5

FIG. 6

FIG. 1 is a perspective view of a repairing and splicing kit container showing our new design;

FIG. 2 is a plan view thereof;

FIG. 3 is a side elevational view thereof, the opposite side being a mirror image of the side shown;

FIG. 4 is a rear elevational view thereof;

FIG. 5 is a front elevational view thereof; and

FIG. 6 is a bottom view thereof.

We claim:

The ornamental design for a repairing and splicing kit container, as shown and described.
